UNITED STATES PATENT OFFICE.

EDWARD E. JOHNSON, OF ST. PAUL, MINNESOTA.

ELECTRIC-HORN SWITCH.

1,254,405.

Specification of Letters Patent. Patented Jan. 22, 1918.

Application filed September 21, 1914. Serial No. 862,651.

To all whom it may concern:

Be it known that I, EDWARD E. JOHNSON, a citizen of the United States, residing at St. Paul, in the county of Ramsey and State of Minnesota, have invented certain new and useful Improvements in Electric-Horn Switches, of which the following is a specification.

My invention relates to a switching device for electric horns of automobiles and has for its object to provide a device for the purpose secured to the top post of an automobile steering wheel which may be moved in any direction to effect contact of circuit closing members and which may be readily operated to effect a light or heavy contact, as may be desired. In carrying out my invention I provide in effect a floating contact piece having a finger or button attached thereto and extended centrally from the supporting post, the circuit closing members comprising a stationary member and a member carried by the said floating device so related that they may be brought into contact by a movement of the finger in any direction.

The full objects and advantages of my invention will appear in connection with the detailed description thereof and are particularly pointed out in the claims.

In the drawings, illustrating the application of my invention in one form,

Figure 1 is a sectional view showing the preferred form of the invention in position. Fig. 2 is a top view of the parts shown in Fig. 1. Fig. 3 is a sectional view of a modification. Fig. 4 is a transverse sectional view of another modification.

As illustrated in Fig. 1, the steering post 10, to which the steering wheel 11 is secured, has set into the hollow top thereof a bored plug 12, formed of insulating material. The plug 12 has a flange-like shoulder 13 which rests upon the top of standard 10. Surrounding the central bore 14 is an enlarged bore 15 having at the bottom thereof a shoulder 16 upon which rests a spiral spring 17 carried by the plug 12. Above the shoulders 18 is a metallic ring 18 which is in electrical connection with one wire 19

of an electric circuit, said wire extending through the interior of post 10 into central opening 14 of plug 12, and through an aperture 20 in plug 12 to a point of connection 21 with the ring 18. It is to be noted that the top of ring 18 extends slightly above the top of plug 12, as indicated at 22.

An upper insulating plug 23 has a metallic plate 24 secured to the lower face thereof by means of countersunk screws 25, and has a rounded walled projection 26 extending into a complementary socket 27 formed in a top cap 28 which is secured to post 10. The projection 26 is held in position within socket 27 by means of the spring 17. The plate 24 is then held spaced from the upper peripheral rim 22 of ring 18, and said plate is in electrical connection with another wire 29 of the circuit by which the automobile horn is operated, wire 29 extending through the interior of post 10, through central opening 14 and the interior of spring 17, and through an opening 30 in plate 24 to a point 31, where wire 29 is secured to plate 24 so as to make electrical connection therewith. A button or finger 32 is secured to the floating cap 28. A screw 33 extends through cap 28 into a slot 34 in the plug 23, which keeps said plug from rotating axially but gives freedom of movement in every other direction.

It will be apparent that the finger 32 may be moved laterally in any direction, which will have the effect of bringing some portion of disk 24 into contact with the rim of ring 18, thus closing the electric circuit and operating the horn. It is immaterial from which side the button 32 is struck. It is also true that a very short contact may be made, which will have the effect of operating the horn only slightly; or a durating contact may be made, which has the effect of producing a much louder blast of the horn.

In the modification shown in Fig. 3, the plug 12 has the spring 17 surrounding said plug and engaging a flange-like shoulder 35 offset from the body of the plug. A contact band 36 is placed inside of the plug continuous with aperture 14. The circuit wire 19 is secured directly to the ring 36 within

the same, passing through the opening 14 and the interior of standard 10, as in the first construction. The other circuit wire 29 is in electrical connection with a metallic post 37 which extends within the ring 36. The post 37 may be continuous with the button or finger 32 which extends through the plug 26 and is secured fixedly thereto by a metallic nut 38. With this form of device it is apparent that similar results may be obtained to those coming from the use of the first-named device. Oscillation of finger 32 in any direction laterally will cause contact of post 37 with the interior of ring 36, closing the horn-operating circuit. Or, by pressing down upon finger 32 contact may be effected through nut 38.

As illustrated in Fig. 4, a construction similar to the preferred form of Fig. 1 is shown, excepting that instead of having a unitary cylindrical ring, as the ring 18 of Fig. 1, a plurality of contact pieces 40, 41, 42 are provided, each being a section of the cylinder and each being insulated one from the other. These several contacts are connected with separate circuit wires 43, 44 and 45, respectively, which in coöperation with the common wire 29 running to plate 24 each comprise a separate circuit. This arrangement thus provides a multiple circuit switch in which any circuit can be operated independently, any pair of adjacent circuits can be operated simultaneously, or all of the circuits involved may be operated simultaneously.

The simplicity and efficiency of my horn-operating switch will be apparent. The finger 32 rises in the most convenient position at the center of the steering post. The hands of the driver are normally upon the steering wheel. He can use either hand to operate the horn switch and may do so by pushing the finger 32 in any lateral or downward direction. This can be done instantly without in any way interfering with the steering operation. Moreover, the nature of the contact may be varied at will, thereby effecting a variation in the blast of the horn. The construction is one which may readily be applied to the steering wheel standards of automobiles without the necessity of reconstruction, and which is perfectly housed and cannot get out of repair.

I claim:

1. An electric switch comprising a post, an insulating plug rigidly secured in the end of said post, a contact member on said plug having a circular contact surface, a spring supported by the said insulating plug, a movable contact member supported by the spring in floating spaced relation to said circular contact member, and an exposed piece adapted to be engaged by the hand of the operator to move the movable

member under both rectilinear and tilting movement to cause a part thereof to effect contact with some part of the circular contact surface.

2. An electric switch comprising a post, a hollow insulating plug rigidly secured in the end of said post, a contact member on said plug having a circular contact surface, a spring supported by the said insulating plug, a movable contact member supported by the spring in floating spaced relation to said circular contact member, an exposed piece adapted to be engaged by the hand of the operator to move the movable member under both rectilinear and tilting movement to cause a part thereof to effect contact with some part of the circular contact surface, and circuit wires extending through said hollow plug and to the respective contact members.

3. An electric switch for automobile horns comprising a standard, a pair of insulating plugs supported upon said standard, a contact plate on each of said plugs, a spring holding said plugs in normal spaced relation, and a finger for moving one of the plugs relatively to the other in various directions to effect contact between the contact pieces regardless of the direction in which the finger is moved.

4. An electric switch for automobile horns comprising a standard, a cap on said standard, an insulating plug fixed on the standard within the cap, an insulating plug spring-held against the cap and movable in various directions to close the switch, contact members on the respective plugs normally held in spaced relation, and a finger rigidly connected with the top plug and extending through said cap.

5. An electric switch for automobile horns comprising a standard, a cap on said standard having a hollow socket in the top thereof, an insulating plug fixed on the standard within the cap, a second insulating plug having a rounded projection seated within said socket, contact plates on said insulating plug having relatively circular contact surfaces, a spring supported by the fixed plug and holding the other plug against the cap and with the projection in said socket so that said contact plates are normally spaced one from the other and movable toward each other under both rectilinear and tilting action, and a finger rigidly secured to the extension of the movable plug.

6. An electric switch for automobile horns comprising a standard, a cap on said standard, an insulating plug fixed on the standard within the cap, a second insulating plug, a spring holding said second plug against the cap and movable toward the other plug under both rectilinear and tiltable action, a

cylindrical contact member surrounding the fixed plug and having an edge thereof exposed above the same, a plate on the other plug having its outer limits extending above said exposed edge, and a finger rigidly connected with the top plug and extending through said cap.

In testimony whereof I affix my signature in presence of two witnesses.

EDWARD E. JOHNSON.
